2 Sheets-Sheet 2

FIG. 3.

UNITED STATES PATENT OFFICE.

GEORGE E. STEPHENSON, OF CHICAGO, ILLINOIS.

DISPLAY LIGHT.

Application filed March 30, 1922. Serial No. 548,067.

To all whom it may concern:

Be it known that I, GEORGE E. STEPHENSON, a citizen of the United States, residing at Chicago, in the county of Cook and State 5 of Illinois, have invented certain new and useful Improvements in Display Lights, of which the following is a description.

My invention relates to an improvement in display lights, and more particularly to 10 a combination display light and advertising sign adapted to be used in showcases, windows, or any other suitable or convenient locations desired.

One of the objects of my invention is to 15 provide a light of the kind described in which a portion of the light is used for illuminating the advertising matter arranged thereon.

The invention has among its other objects 20 the production of a device of the kind described which is neat and attractive in appearance, simple, convenient, compact, durable, reliable, efficient and satisfactory for use wherever found applicable.

25 Another object of my invention is to provide a device of the kind described which is portable and easy to handle, so that it may be placed in any convenient position and changed from time to time, if so desired.

30 Many other objects and advantages of the construction herein shown and described will be obvious to those skilled in the art from the disclosures herein given.

To this end my invention consists in the 35 novel construction, arrangement and combination of parts herein shown and described, and more particularly pointed out in the claims.

In the drawings, wherein like reference 40 characters indicate like or corresponding parts,

Fig. 1 is a sectional view showing one manner of positioning my improved light;

Fig. 2 is a front elevation of the same;

45 Fig. 3 is a sectional view taken substantially on the line 3—3 of Fig. 1;

Fig. 4 is a sectional view taken substantially on the line 4—4 of Fig. 2;

50 Fig. 5 is a sectional view taken substantially on the line 5—5 of Fig. 2;

Fig. 6 is a modified form similar to that

shown in Fig. 1, but with the light mounted adjacent the ceiling;

Fig. 7 is a sectional view illustrating a modified form having a curved reflector 55 therein, and

Fig. 8 illustrates another modified form having a plurality of sign-receiving windows therein.

In the drawings, wherein I have illustrated the preferred embodiments of my invention, there is represented a display light adapted to be used for lighting up showcases, windows, or other suitable places, and comprises a casing or container, 60 preferably of the form shown, wherein 1 indicates the bottom wall, 5—6 the top wall, 3 the rear wall and 4 the end walls. It will be noted that the casing is open 65 entirely across the front thereof. The designations of "front" and "rear" walls are merely for the matter of convenience, because, as will be apparent from a full disclosure of the invention, the light may be hung or placed so that the relative designations will be reversed, for example see Figs. 6 and 8.

The top wall is parallel with the bottom wall for a distance, represented at 5, and thence diverges or flares outwardly therefrom toward the front side, as at 6, so that there is formed a tapered or flared chamber or opening within the casing. A partition 7 is arranged across the inside of the walls of the casing, as shown in the drawings said 75 partition preferably having its edges flanged so as to lie against the walls of the casing and act as a reinforcement therefor. Any form of fastening means may be used for securing the partition in place, as for instance by soldering, riveting or the like. The partition divides the casing into two 80 compartments comprising a rear compartment 8, which is concealed, and a front compartment 9, in which suitable lamps or 85 lights 10 are adapted to be arranged. The wiring connections 11 are adapted to be arranged within the concealed compartment 8, and the partition performing the function of a panel to carry the wiring, also carrying one or more sockets 12 spaced apart thereon 90 in which the lamps 10 are adapted to be

- screwed. One of the end walls 4 is provided with an opening therethrough into the concealed compartment 8, into which the lead wires of the wiring circuit may be inserted.
- 5 Reinforcing means, as for instance a stiff wire 12, may be arranged about the bounding edges of the open side of the casing, as shown in the drawings, the edges of the casing rolled over said wires to enclose them 10 and form a rounded edge.
- One or more of the walls of the casing have an opening 13' formed therein to receive advertising matter or display matter thereon, whereby said advertisements will 15 become illuminated whenever the lights 10 are turned on. In the form shown in Fig. 1, the opening is cut through the top wall 2, the edges of said opening being bent backwardly upon themselves, as at 13. Guides, 20 comprising channel-shaped members, are positioned at the opposite sides of said opening 13' to removably receive a translucent plate or window 15. The channels 14 are preferably secured in position by having one of 25 their parallel legs secured in place between the wall of the casing and the turned-over edge 13, as shown more clearly in Fig. 4. Any suitable advertisement may be arranged or superimposed on the translucent plate 15, 30 in any desired manner as for instance said advertisement may comprise a sheet 16 having cutout portions therein, through which the light may shine. Any other suitable type of advertisement may be arranged over 35 the window 15 on either the inside or outside, either separate therefrom, or, if desired, said advertisement may be imprinted directly upon the plate 15, or formed in any other suitable manner thereon.
- 40 It is obvious that when the lights are turned on, a portion of the rays will be directed against the translucent plate 15, illuminating the advertisement, and that the rays will also be directed outwardly of the 45 flared open side to illuminate the goods on display. Any suitable type of electrical means may be used in this device, as for instance a make-and-break flasher, colored lights or the like, as preferred.
- 50 The device may be mounted at any suitable point, as for instance upon the bottom or floor 17 of the window or showcase toward the glassed front thereof, so that the advertisement will be below the observer's 55 eye, as shown in Fig. 1, or the casing may be suspended from the ceiling or top wall of the window or showcase, as shown in Fig. 6, and wherein the advertisement will be above the observer's eye. In order that the heat generated 60 shall not injure the material of the supports lugs 18 are provided on the bottom wall of the casing of the showcase, so that there is an air space between the bottom wall 1 and the material of the supporting wall.
- 65 In order to prevent the accidental with-

drawal of the plate 15 during the handling or carrying of the device, I have arranged clips 20, or other suitable or equivalent fastening means, to engage the edges of the plates, as shown.

70

In the modification shown in Fig. 7, the device is similar to that previously described, except that partition 19 is arcuate in cross-section to form a different type of reflector for the lamps 10. The surface of the partition 19 may be coated, silvered or polished, as desired, or there may be a separate reflector superimposed over the partition.

75

In the modification shown in Fig. 8, both the walls 1 and 2 have openings formed therein to receive the advertisements. This type of device is particularly adapted for those showcase or the like, wherein the observer may view the goods on display from opposite sides of the case.

80

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

85

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

90

What I claim as new and desire to secure by Letters Patent is:

95

1. In a device of the kind described and in combination, a sheet metal casing having an opening through one of its sides and having bounding edges of said opening bent back upon itself, channel members at the edges of said opening, each having one leg secured between the casing wall and said bent-back edge of the opening, and a window arranged to removably slide in said channels to cover said opening and adapted to have an advertisement superimposed thereon.

100

2. In a device of the kind described and in combination, a sheet metal casing having an opening through its side wall, the bounding edges of said opening bent back upon themselves, channel members at said edges, each having one leg secured between the casing wall and the bent-back edge of the opening, a window plate arranged to removably slide in said channels to cover said opening and adapted to have an advertisement superimposed thereon, and means for preventing accidental withdrawal of said plate.

105

3. In a device of the kind described and in combination, a sheet metal casing having openings through a plurality of its side walls, the bounding edges of said openings bent back upon themselves, channel members at said edges, each having one leg secured between the casing wall and the bent-back edges of the openings, window plates removably slidable in said channels to cover said openings and adapted to have an ad-

vertisement superimposed thereon, means for preventing accidental withdrawal of said plates, and means for lighting the interior of said casing, whereby the light will be directed against said window plates to illuminate said advertisement.

In testimony whereof, I have hereunto

signed my name in the presence of two subscribing witnesses.

GEORGE E. STEPHENSON.
